CONTAINER FEEDING MECHANISM FOR LABELING MACHINES

Frederick W. Wehmiller, Ladue, and William J. Nekola, Normandy, Mo., assignors to Barry-Wehmiller Machinery Company, St. Louis, Mo., a corporation of Missouri

Application September 17, 1953, Serial No. 392,923

9 Claims. (Cl. 198—30)

(Filed under Rule 47(a) and 35 U. S. C. 116)

This invention relates to a method of feeding objects to a multiple labeler in such a way that the labeler can operate at its optimum speed and the objects can be handled in rapid succession without damage or substantial pounding, jostling, and the like; and the invention is also particularly concerned with novel mechanism for carrying out the steps in the operation of the method.

One of the objects of the invention is to provide means for effecting the crowd feeding of objects in a haphazard order to a machine adapted to apply labels to a plurality of objects simultaneously taken into the machine in an orderly manner from the haphazard crowd.

Another object hereof is to provide continuously operating means for delivering containers in a haphazard and crowding type of container movement into a multiple labeling machine, and other means for arranging the objects in an orderly condition to be taken into the labeling machine in successive groups.

A further object is to provide means for protecting both the containers and the labeling machine, the first from hard rough handling and the second from operation in the event of non-delivery of an object to any of the label applying means within the labeling machine.

Other objects are to be found in the combination of parts and mechanisms, and in the individual parts and mechanism hereinafter disclosed and claimed.

Broadly, this improvement consists in providing a multiple labeler having aisles for the objects with power driven feed conveyor means for each aisle, a delivery conveyor for bringing a crowd of objects into all of the feed conveyor means for haphazard crowd feeding thereof into the several aisles of the labeling machine, and means in the nature of safety expedients located in each of the aisles for protecting the machine against unnecessary operation and for releasing the objects in an orderly way to be picked up in the labeling machine for labeling thereof.

A preferred embodiment of the invention is shown in the drawings, wherein:

Fig. 1 is a front perspective view of a multiple labeling machine showing the preferred embodiment of the invention adapted for the characteristics of the machine, certain portions of the assembly being broken away to reveal details of the mechanism and only so much of the machine being disclosed as will serve to understand the principles of the improvements;

Fig. 2 is a fragmentary and partly broken away top plan view of the mechanism associated with the labeling machine;

Fig. 3 is a fragmentary sectional elevational view of the mechanism as seen at line 3—3 in Fig. 2;

Fig. 4 is a fragmentary front elevational view of the mechanism of Fig. 1;

Fig. 5 is a fragmentary sectional view longitudinally of the feed conveyors and including the pertinent portions of the labeling machine to show the association of parts, the view being taken at line 5—5 in Fig. 4;

2

Fig. 6 is a top plane view of the fragmentary portions shown at line 6—6 in Fig. 5;

Fig. 7 is a fragmentary detail in plan of the partition adjusting means for the feed conveyor aisles;

Fig. 8 is a fragmentary elevational view of the illustration in Fig. 7;

Fig. 9 is a fragmentary view of a typical container transfer means showing the container engaging fingers;

Fig. 10 is a sectional detail at line 10—10 in Fig. 9;

Fig. 11 is a further sectional detail at line 11—11 in Fig. 10;

Fig. 12 is a schematic view of a typical container transfer means showing the periodic operating cycle thereof relative to a container in each of two adjacent rows thereof;

Fig. 13 is a fragmentary plan view of the control system for stopping the machine under certain operating conditions;

Fig. 14 is an elevational view of the control system shown in Fig. 13; and

Fig. 15 is an enlarged and schematic elevational view of a typical group of cooperating parts in the control system shown in Fig. 14.

Container supplying means for labeling machines heretofore provided for commercial applications have possessed the defect of failing to supply containers at rates which would permit the full utilization of the capacity of the labeling machines. These means have also possessed the serious drawback of handling the containers with much roughness and knocking about so that excessive loss and breakage has resulted. Moreover, prior container supplying means of the type shown in Fig. 1 and other views of the drawing operate on the premise that the containers must be tipped, canted or must undergo a change of position. These prior devices have also been subject to faulty operation with the result that additional loss through breakage, damage and machine idleness has been experienced.

The present improvements, as exemplified in and by the preferred embodiment, are adapted to overcome the defects and difficulties heretofore encountered and successful results have been obtained thereby. The mechanism to be described in detail provides an improved system or method of handling the supply of containers for

a labeling machine. This system embodies the concept of bringing into a collecting zone near the labeling machine the containers in a continuously flowing stream having a haphazard arrangement so that there is produced a crowding effect among the containers, but the crowding effect is not harsh or damaging due to the conveying means being capable of sliding beneath the containers when obstructions occur. The haphazard crowd of containers under urging from the delivering conveyor is guided gently but positively into a plurality of orderly rows or files upon feed conveyor means which urges the container rows toward the machine where labels may be applied. The handling and conveying of the containers is carried out at substantially the same elevation with the elevation of the label applying zone in the machine.

With a system of this character the containers may be delivered at a rate in excess of the desired rate of labeling by the machine so that the potential capacity of the machine can be utilized to the fullest extent if desired.

For example, by the system herein disclosed a labeling machine capable of operating at the rate of 200 containers per minute may be supplied at the rate of 250 containers per minute without jamming the supply means or forcing containers into the machine faster than the selected rate of machine operation. Great flexibility in arrangement and choice of labeling machines is obtained with a system of this character, and the demands of the

canning, bottling and similar industries may be met in a simple and efficient manner.

A mechanism which will satisfy the foregoing requirements is shown in connection with a labeling machine A (Fig. 1) arranged to apply labels to a plurality of bottles B simultaneously. The labeling machine, per se, forms no part of the present invention, except as certain portions and parts thereof may become operationally associated with the improved mechanism and parts to be described. The machine has a frame 10 which supports the stationary and moving parts thereof, including the usual motor drive and connected power transmitting means. The label applying means 11 is shown at the front or inlet side of the machine A.

A suitable frame 12 (Fig. 1) is attached to the machine frame 10 somewhat below the horizontally directed track bars 13 (Fig. 3) provided within the machine A at the label applying zone L thereof. The frame 12 carries supports 14 (Figs. 1, 2 and 3), one at each side of the inlet for the machine A, and these supports carry bearing stands 15 and 16 for the front and rear shafts 17 and 18, respectively, of the feed conveyor system. Shaft 17 carries a plurality of sprockets 19 spaced along its length, shaft 18 also carries a similar number of spaced sprockets 20, and conveyor means 21 are connected between the sprockets. Track bars 13 extend into close adjacency to the conveyor means 21 at the outlet ends thereof (Fig. 5).

Each feed conveyor means 21 is provided with a pair of partitions 22 and 23 (Figs. 1, 2 and 3) arranged at each longitudinal side thereof to define aisles through which the containers are moved by the feed conveyor means. The partitions are laterally adjustable (Figs. 2 and 3) in pairs, one set of partitions 23 being carried on individual frames 24 attached to a common bar 25 slidable in the guide channel attachment 26 fixed to supports 14. The other set of partitions 22 are carried on individual frames 27 attached to a common bar 28 also slidable in attachment 26. Suitable thrust gear means 29 (Figs. 2, 7 and 8) couple the bars 25 and 28 to a crank 30 so that the turning of crank 30 spreads or draws the pairs of partitions 22 and 23 together to vary the width of the aisles to accommodate different size containers.

The inlet end of each feed conveyor 21 is defined by guide means acting to direct the containers into the aisle between the partitions 22 and 23 therefor. This guide means includes a curved member 33 carried on each partition 23 and a cooperating flexible and curved member 34 fixed to the outer end of each member 33 and movably attached to an anchor 35 for sliding motion therein. An anchor 35 is attached to each of the partitions 22. Thus, an entrance throat is formed between the pairs of members 34 and 33, and these throats change as the partitions are adjusted by sliding action of guide member 34 in the associated anchor 35.

A container delivery conveyor 37 of large capacity is suitably arranged on the frame 12 spanning the space between supports 14 across the inlet ends of all of the feed conveyors 21. This conveyor 37 is made up of chains having flat plate flights thereon which form a substantially continuous flat and horizontal surface designated as a container collecting zone C (Figs. 1 and 2). Conveyor 37 is of known construction and need not be described in greater detail. Container guide fence rails 38 at the outer margin and similar rails 39 at the inner margin of the conveyor 37 confine the delivery of containers to the collecting zone C. The containers are brought into this zone in a haphazard crowd (Fig. 1) in which the containers are in contact and are continually urged into a crowd by the friction of the conveyor 37 sliding relative thereto as the conveyor continues to move through zone C on its return pass. The pressure within the crowd of containers forces the same toward the guide means for each feed conveyor 21 so that a flow is created into all of the aisles where the action of the feed con-

veyors carries the containers in orderly rows toward the labeling machine A between the pairs of partitions 22 and 23. The quantity of containers arriving and collecting in zone C is greater than the flow into the feed conveyors 21 so that each aisle is maintained filled during normal operation.

In Figs. 3 and 5, the delivery conveyor 37, the feed conveyor 21 and the bar 13 in the labeling zone L of the machine A are arranged at the same level so that the containers B do not have to change elevation or deviate from a normal upright position. In Fig. 5, the bar 13 in machine A is given a slight upward inclination at 13a to facilitate the break-away action of the pusher forks 40 from the containers at the discharge end of the conveyor chain 41 provided as a part of the machine A. This chain 41 is carried by sprockets 42 and 43 on shafts 44 and 45, respectively. This assembly is typical of similar means aligned with each feed conveyor 21. Other means not necessary to be shown, in the machine effects the final discharge of containers from machine A.

The means for transferring the leading container in each aisle on the feed conveyors 21 is shown in Figs. 1, 3 and 4, and in greater detail in Figs. 5, 6, 9, 10 and 11. The frame 10 carries a pair of bearing brackets 46 at each side of the inlet to the machine A and above the feed conveyors 21. A rock shaft 47 (Figs. 1 and 3) is operably supported in the brackets 46 with one end 48 provided with a lever 49 to receive a link 50. A knuckle fitting 51 connects link 50 with the upper end of a push rod 52, and push rod 52 is connected to a yoke 53 which engages a suitable cam follower, schematically shown at 54, driven by a rotary cam device 55 of the type having an internal cam track (not shown). The cam 55 is driven from a power shaft 56 in machine A. Cam rotation effects periodic rocking motion in shaft 47 in timed relation with the label applying mechanism of the machine. This latter mechanism is not described, but is of known construction.

Rock shaft 47 carries a plurality of arms 58, one being located on each side of the feed conveyors to swing through the space between adjacent partitions 22 and 23 (Fig. 4). Each partition is formed with an elongated slot 60 (Figs. 3, 4 and 5). The lower end of each arm 58 carries a sleeve 61 surrounding a portion of a pivot pin 62 of reduced diameter. The pin carries a pair of pivotally movable fingers 63 having hubs 64 in interfitting relation so that the fingers may move in opposite directions. Each hub has a projecting cam element 65 which abuts, once in each stroke of arm 58, a cam block 66 (Figs. 3 and 5) fixed to a stationary member located between each of the feed conveyors 21. The hubs 64 are maintained under frictional restraint by a spring 67 (Figs. 9 and 11) in sleeve 61 bearing upon a friction plate 68 and pressing the hubs upon a second friction plate 69. A stop pin 70 in the end face of sleeve 61 limits the spreading movement of the fingers 63 upon the cam elements 65 engaging the block 66 (Fig. 12). Thus, the fingers 63, as shown in Fig. 12, may upon motion of arm 58 toward the right fold toward each other as they pass between containers B on adjacent feed conveyors. The folded condition is maintained until the outer limit of arm movement is reached, at which time the cam elements 65 strike the cam block 66 and spread fingers 63 into positions behind the containers B. Reversal of motion of arm 58 brings the fingers 63 against the containers and pushes the latter into the labeling zone L (Fig. 5) of the machine, shown at the left in the schematic view of Fig. 12. This action is repeated periodically for all of the devices on the arms 58. The slots 60 in the partitions 22 and 23 allow the fingers 63 to project into the aisles to engage the containers therein.

The action of the transferring means, exemplified by the arms 58, is simplified by the provision of gate means for the outlet end of each feed conveyor 21. The gate means includes a pair of inlet pin elements 73 (Figs. 2, 3, 4, 5 and 6) arranged on each side of each feed conveyor 21 and all of these pins are mounted on a support 74 ex-

tending the width of the machine A to be fixed to vertically movable rods 75 sliding in guides 76 in the frame 12. A pair of outlet pin elements 77, arranged on each side of each feed conveyor 21 and spaced from the pins 73, are carried on a support 78 extending the width of the machine A. The ends of support 78 are fixed to vertical posts 79 connected to horizontally movable slides 80 (Fig. 3). Each slide 80 is internally threadedly connected to a screw shaft 81 carried in a bearing member 82. Each member 82 is attached to a vertically movable rod 83 sliding in guide 84 in frame 12. Each screw shaft 81 carries a worm gear 85 which meshes with a worm on a common drive shaft 86. The shaft 86 is connected by chain drive 87 to a short control shaft 88 which, in turn, is operated by crank 89 (Figs. 2 and 4). Thus, outlet pins 77 may be moved toward or away from pins 73 to adjust the spacing thereof to the size container being handled.

The pairs of inlet and outlet pin elements 73 and 77 are periodically raised and retracted relative to the horizontal top plane of the feed conveyors 21 to allow pins 73 to pass one container at a time and hold back the remainder, and to allow pins 77 to release one container at a time to be advanced by the pushing action of the transfer arms 58. Each pin element 73 carries a cam element 90 (Figs. 3, 5 and 6) which imparts a slight forward motion to each container in the gate zone to permit proper action of the finger elements 63 in engaging behind the containers. The slide rods 75 and 83 are connected at the lower ends by rock levers 92 attached to a common rock shaft 93 (Figs. 1, 3 and 4). One end of shaft 93 is connected by a link 94 to a push rod 95, in turn, connected by yoke 96 to a cam follower 97 operated in response to an internally profiled cam 98 rotated by drive shaft 56 for the previously described cam 55. The action of the rocker 92 causes alternate vertical movement of pins 73 and 77, whereby as pins 73 lower a container passes on to be stopped by raised pins 77. Similarly as pins 73 rise to intercept following containers, the pins 77 lower to allow the arms 58 to advance the containers, as shown in Fig. 5.

It should now be apparent that all of the operating devices, parts and mechanisms derive motive power from a suitable power source (not shown) within the machine A so that accurate synchronism and timing may be achieved in a simple manner. The delivery conveyor 37 may be driven from machine A, depending upon the characteristics of the installation. In most cases, this conveyor is preferably separately driven.

From the foregoing description, it should be apparent how the present mechanism operates to carry out the principles of the improved system for supplying containers smoothly and gently into a labeling machine. In order to guard against damage to containers and operation of the machine A when less than a full complement of containers is delivered into the labeling zone L, safety shut-down means has been incorporated to be responsive to the presence or absence of a container within the range of swinging motion of arms 58 (Figs. 4, 5, 13, 14 and 15).

The safety means includes a plurality of feeler elements 100, each pivoted on a support in such position that its end portion 101 may move above the top level of one of the conveyors 21 with which it is related. There is an element for each such conveyor 21 and, hence, for each aisle of the mechanism. Each element 100 is periodically engaged by a push pin 102 mounted in a block 104. Each block 104 is adjustably carried on a fixed rod 105, in turn, carried by the reciprocating support 74 extending the width of the machine. The support 74 is used also to carry the gate pins 73. In Fig. 15, the push pin 102 carries an adjusting nut 107 bearing on a spring 108 covered by a dirt cup 109 of flexible material. Below block 104 a second adjusting nut 110 is provided so that the vertical limits of the position of pin 102 may

be accurately set. Spring 108 maintains an upward force on the pin 102 to the limit set by nut 110 so that the pin 102 may strike or poke the feeler element 109 upwardly (broken line position) if no container B is in 5 the conveyor aisle. The lower end of push pin 102 carries a plate 111 in fixed position thereon, one end of plate 111 being slidably guided on a guide pin 112 fixed to the block 104. The opposite end of plate 111 carries an adjustable tappet 113 adapted to engage a trip 10 lever 114 fixed to an angularly movable control bar 115 pivoted at its ends in the fixed structure of machine A. At one end of control bar 115, a switch tappet 116 is mounted to project into actuating relation with a power control switch 117. In operation, so long as all of the 15 feeler elements 100 are held down by containers B, the push pins 102 will be periodically depressed against springs 108 at each upward stroke of support 74 and the control bar 115 will be unmoved or maintained in the full line position of Fig. 15 to prevent operating switch 117 to its 20 open circuit position. The machine will thus operate normally. Should one aisle be imperfectly filled with containers so that a gap develops in the row of containers, the feeler element 100 will be allowed to raise (broken line position of Fig. 15) under the force of its 25 associated push pin 102. This action is independent of all other feeler elements 100 due to the yieldable action of the pins in block 104. As a result the switch 117 will be actuated to shut down the machine at a preselected place in the operation before the label applying mechanism can complete its full cycle to bring a gummed label into final position at the label applying zone L. Correction of the faulty condition can be made before the label glue is deposited on the mechanism or faulty distribution of containers to the several aisles for the feed 30 conveyors can be corrected.

The above description has been given for a preferred embodiment of the present improvements, but certain changes in the arrangement of parts and components will appear obvious once the foregoing is understood. Accordingly, the invention is not to be limited in its scope or range of equivalents for the parts and means described except as the same is required by the claims hereof.

What is claimed is:

1. In a container feeding mechanism for a labeling machine having an inlet side for a plurality of containers and a label applying station for simultaneously labeling a plurality of containers, the improvement of a plurality of container feed conveyors having outlet ends adjacent the inlet side of the machine, means to operate said feed conveyors together, container transfer means adjacent the outlet ends of each of said feed conveyors periodically movable together between a position engaging the leading containers on said feed conveyors and a position transferring the leading containers to the label applying station in the machine, power operated means in the machine connected to said feed conveyors and transfer means to operate the same, and safety means for cutting off the source of power for said power operated means to stop the machine, feed conveyors and transfer means, said safety means including a control switch connected to said power operated means, switch operating means operably disposed in each of said feed conveyors and movable between switch open and closed positions, finger means adjacent each feed conveyor in the path of container movement and engageable therewith, and actuating means connected between each of said finger means and said switch operating means, said actuating means being resiliently urged in a direction to displace any of said finger means which is free of engagement with a container and actuate said switch operating means into switch open position to stop the machine, feed conveyors and transfer means.
2. An article feeding mechanism for a machine having multiple label applying means, frame means connected to the labeler machine at the inlet to the machine, a series

of spaced, horizontally directed article feeding conveyors carried by said frame means and having the outlet ends thereof in alignment with the label applying means; an article supply conveyor extending adjacent said feed conveyors in the same horizontal plane, said supply conveyor forming an article collecting zone communicating with all of said feeding conveyors and being adapted to slide relative to the bottoms of the articles for crowding the articles together to urge them from the collecting zone into the feeding conveyors to maintain a full complement of articles in each feeding conveyor; article transfer means operatively arranged on said frame means common to all of said feeding conveyors, said transfer means having article engaging elements movable adjacent said feeding conveyors to select one article at a time in the outlet end of each feeding conveyor and move the articles into the label applying means; power operated means connected to said transfer means to effect simultaneous movement of said elements, and control means for said feeding mechanism adapted to stop said mechanism upon the absence of an article in the outlet end of any one of said feeding conveyors, said control means including a displaceable element in each feeding conveyor in the path of articles to be held against displacement by the presence of articles therein, and testing means carried by said frame means adjacent said displaceable elements to periodically test said displaceable elements and stop said mechanism upon the absence of an article in the outlet end of any of said feeding conveyors.

3. Article feeding apparatus for a multiple labeler machine comprising frame means on the machine at the article receiving zone thereof; a plurality of article moving conveyors in said frame means in parallel flow relation to the labeler machine; periodically alternating gate means in each conveyor adapted to select one article at a time for release to the labeler machine while restraining the other articles; periodically movable article transfer means for said conveyors adapted to engage the released articles and transfer them as a group into the labeler machine; testing means in each conveyor in advance of said gate means to test for the absence of an article at said gate means, said testing means including a group of finger elements movable with said gate means and a similar group of abutments held by the articles and free to move in the absence of the articles; power operated means adapted to drive said article conveyors, gate means and transfer means, including a control operable to stop said power operated means upon any one of said finger elements being able to move its abutment.

4. Container feeding mechanism for use with a labeler machine having label applying stations through which containers to be labeled pass; said mechanism including a plurality of container feed conveyors adapted to move containers in a continuous flow toward the label applying stations and to slip beneath the containers upon obstruction being imposed in the flow of the containers, said feed conveyors being equal in number to the number of label applying stations in the labeler machine, and each of said feed conveyors having an inlet end and an opposite discharge end directed toward a label applying station in the labeler machine, container delivery conveyor means positioned adjacent the inlet ends of said feed conveyors, said delivery conveyor being adapted to deliver containers in a haphazard crowd adjacent the inlet ends of said feed conveyors in excess of the rate at which said feed conveyors move the containers toward the discharge ends thereof to cause crowding of the containers into said feed conveyor, and said container feed mechanism further including periodically operable transfer means adjacent the outlet ends of said feed conveyors to move between the conveyors and the machine and transfer containers from all of said feed conveyors into the labeling machine together, and control means operable at times to stop the operation of the feeding mechanism and said transfer means when less than all of said feed conveyors have a container to be engaged by said transfer means, and said control means being operable at all times to restrain the feeding movement of following containers with transfer of the containers engaged by said transfer means.

70
75

8
veyors have a container at the outlet end and operable at all times to restrain the feeding movement of following containers concurrently with transfer of the container at the outlet end.

5. Container feed mechanism for use with a labeler machine having a group of label applying stations to be supplied simultaneously with containers to be labeled; said mechanism including a group of container feed conveyors adapted to move containers in a continuous flow toward the label applying stations and to slip beneath the containers upon obstruction being imposed in the flow of the containers, said feed conveyors being equal in number to the number of label applying stations in the labeler machine and each of said feed conveyors having an inlet end remote from the labeler machine and a discharge end communicating with the label applying station in the machine, a container delivery conveyor extending across the inlet ends of all of said feed conveyors to deliver containers in a crowd to said feed conveyors to be conveyed away from the crowd toward the label applying stations in each of said feed conveyors in single file, said delivery and feed conveyors being in substantially the same plane and the delivery conveyor being adapted to crowd containers to said feed conveyors in excess of the rate at which the feed conveyors carry the containers away and to slide across the bottoms of the containers during the crowding movement of the containers into said feed conveyors, and said mechanism further including periodically operable means adapted to move between said feed conveyor discharge ends and the label applying stations in the labeler machine to transfer the containers in groups to all of the label applying stations, and control means for said periodically operable means comprising feeler means in each of said feed conveyors responsive in the absence of containers in said feed conveyors to stop operation, and gate means operable with said feeler means to restrain containers in each of said feed conveyors following in line after the containers being transferred.

40
45
50
55
60
65
70

6. Container feed mechanism adapted for use with a multiple labeler machine, said mechanism including a group of container feed conveyors in spaced apart and parallel feeding relation to feed containers simultaneously into the machine for labeling thereof; a container delivery conveyor adjacent to all of said feed conveyors to deliver containers to all of said feed conveyors, said delivery conveyor supporting the containers in a crowd during conveyance, partition means fixed at each side of each of said feed conveyors to define an aisle for each of said feed conveyors and to separate guide means mounted on said partition means adjacent said delivery conveyor to direct the containers from the crowd into the aisles for each feed conveyor, means to periodically transfer the leading containers in each aisle as a group into the labeler machine, said transfer means having elements operable to fold in one direction for movement of said transfer means between the aisles away from the labeler machine and to unfold and engage the leading containers for movement in an opposite direction, said partition means serving to steady the containers during movement under the action of said transfer means, and control means operable at times to stop the operation of the feeding mechanism and said transfer means when less than all of said feed conveyors have a container to be engaged by said transfer means, and said control means being operable at all times to restrain the feeding movement of following containers with transfer of the containers engaged by said transfer means.

7. Container feed mechanism for a labeler machine for simultaneously applying labels to a group of containers, said mechanism including the improvement which comprises a container delivery conveyor adjacent the machine operable to convey containers to the machine in a haphazard crowding stream, said delivery conveyor having an open side presented toward the machine and being

adapted to slide beneath the containers during obstruction to further container movement therewith, partition means extending between the open side of said delivery conveyor and the machine and arranged in spaced relation defining a group of aisles for containers, individual feed conveyor means in each of said aisles extending from said delivery conveyor toward the labeler machine to move the containers away from the crowding stream arriving on said delivery conveyor and to positively feed the containers toward the machine, said feed conveyor means being adapted to slide beneath the containers during obstruction to container movement therewith, power means to operate said feed conveyor means as a group, control means responsive to a full complement of containers in said group of aisles to keep said power means in operation, gate means operably connected to said control means to periodically release one container at a time in each aisle for transfer to the labeler machine and to restrain following containers, and periodically operable container transfer means driven by said power means, said transfer means including foldable elements adapted to move in the spaces between aisle defining partitions and engage the containers in said aisles, the engagement with containers in one direction of movement causing folding of said elements and in the opposite direction said elements unfolding to engage the containers.

8. A container feed mechanism for a labeling machine having an inlet side for containers and a label applying station therebeyond, a frame structure on said machine, a plurality of container feed conveyors carried by said frame in spaced relation and having outlets adjacent the inlet side of the labeler machine, said feed conveyors being operated together to feed a plurality of containers toward the label applying station simultaneously, a container delivery conveyor extending adjacent each of said feed conveyors carried by said frame, said delivery conveyor having a container conveying capacity at least equal to the capacity of all of said feed conveyors to crowd containers toward the feed conveyors, partition means carried on said frame adjacent the sides of each of said feed conveyors to guide the containers thereon, said partition means having an inlet end adjacent said delivery conveyor and an outlet end adjacent the label applying station, guide means carried by said partition means at said inlet ends to guide the containers into said feed conveyors between said partition means from the crowd of containers on said delivery conveyor, and means adapted to regulate the removal of containers one at a time from each of said feed conveyors so as to feed a group of containers to the inlet side of the labeling machine, said regulating means comprising simultaneously movable elements respectively adapted to feel out containers adjacent said feed conveyor outlets and to restrain containers following the leading containers in said feed conveyor outlets, the container feeler elements being re-

silently supported by said regulating means to yield under the presence of containers and to remain unyielding under the absence of containers, and means to stop the feed mechanism actuated by any of said feeler elements remaining unyielding.

9. In a container feeding mechanism for a labeling machine having a horizontally directed support for receiving containers in an erect position and means for moving the containers along the support during labeling thereof, the improvement of a container feed conveyor having an outlet end adjacent the horizontally directed support and an inlet end remote therefrom, a container delivery conveyor adjacent the inlet end of said feed conveyor to crowd containers in an erect position into said feed conveyor, container transfer means movable back and forth between a position engaging an erect container at the outlet end of said feed conveyor and a position transferring such erect container to the means in the machine for moving containers along the horizontally directed support, gate means adjacent the outlet end of said feed conveyor and within the range of movement of said transfer means, said gate means including spaced elements periodically movable into and out of the path of container travel on said feed conveyor to free the leading container for transfer to the machine by said transfer means and block the feeding movement of the following containers on said feed conveyor, and means to periodically test for the presence of a container at said gate means comprising a movable member adjacent said feed conveyor adapted to be held against movement by a container, a periodically movable element adapted to engage said movable member and test it for movement, and means resiliently supporting said element from said gate means to permit said element to move relative to the support upon said member being held against movement by the containers.
